UNITED STATES PATENT OFFICE.

HELEN M. DEAM, OF ROCKPORT, ILLINOIS.

FLOOR-SCRUBBING MACHINE.

1,278,606.

Specification of Letters Patent. Patented Sept. 10, 1918.

Application filed November 26, 1915. Serial No. 63,535.

To all whom it may concern:

Be it known that I, HELEN M. DEAM, a citizen of the United States, residing at Rockport, in the county of Pike and State 5 of Illinois, have invented new and useful Improvements in Floor-Scrubbing Machines, of which the following is a specification.

This invention comprehends the provision of a floor scrubbing machine of novel construction, and by means of which the performance of this duty is rendered considerably less laborious.

The invention aims to provide a machine of this character embodying among other 15 features, a scrubbing element operable as the machine is moved over the surface to be cleaned, and a water supply tank, with means for controlling the flow of water to the scrubbing element.

20 In carrying out my invention I provide a machine of the class in question, constructed to receive a cleaning powder or substance, together with means for distributing the substance upon the floor or surface to be 25 cleaned, in advance of the scrubbing element in any desired quantity, as the machine is moved over the floor.

Another object of importance resides in the provision of means for relieving the 30 scrubbing element of its dirty water and directing the same into a suitable receptacle or compartment in the machine, from which it may be readily discharged when desired.

The invention further contemplates the 35 provision of a resilient means operable to effectively maintain the scrubbing element in engagement with the surface being cleaned, thereby rendering the machine exceptionally efficient for the purpose intended.

40 Other objects will appear as the nature of the invention is better understood from the following description, wherein the specific construction, combination and arrangement of parts, of one embodiment of the invention 45 are more fully set forth.

In the drawings forming a part of this specification, like numerals of reference indicate similar parts in the several views and wherein:

50 Figure 1 is a top plan view of the machine showing the water tank partly broken away to show the interior thereof.

Fig. 2 is a bottom plan view.

Fig. 3 is a side elevation.

55 Fig. 4 is a longitudinal sectional view.

Fig. 5 is a transverse sectional view.

Before entering into a detail description of my invention I desire to have it understood that the device hereinafter described and illustrated, is merely one embodiment 60 of the invention, and that various changes in the construction and arrangement and proportion may be resorted to when desired as fall within the scope of the appended 65 claim.

The machine in this particular instance embodies a bottomless casing indicated generally at A and including side walls 5, end walls 6 and a top 7, 8 indicating a reinforcing band disposed exteriorly of the casing 70 and secured thereto by means of the rivets or other suitable fastening elements 9. Journaled between the side walls 5 adjacent the opposite ends of the casing are shafts 10, upon which are fixed wheels 11 to permit the casing to be readily and easily moved over the surface to be cleaned. Passed transversely through the casing at a point approximately centrally thereof, is a shaft 12 75 projecting a slight distance beyond the opposite sides 5, and upon the extremities of this shaft is swingingly secured, in any suitable manner, a yoke 13 of which the handle 14 forms a part.

As shown in this instance the scrubbing 80 element is in the nature of a mop, consisting of an endless belt 15 movable over the shafts 10. The opposite side walls 5 are each provided adjacent their lower edge with spaced 85 aligned vertically disposed elongated slots 16 which receive the spaced parallel transversely extending rods 17, and upon which rods are mounted a resilient shoe for the purpose of effectively maintaining the lower run of the mop in engagement with the surface being cleaned. The shoe consists of a plate of resilient metal, the bottom 18 of which normally bears against the lower run 90 of the belt, while the upturned ends are coiled about the rods 17. I further provide springs 20 having their ends passing through slots in the shoe and coiled loosely upon the rods 17 and having an upwardly bowed portion bearing against the shaft 12 thereby holding the shoe in operative position with 95 relation to the mop. The slots 16 permit the shoe to have a slight vertical movement, when excess pressure is brought to bear upon the machine.

100 Mounted upon the top 7 and fitted between the flanges rising therefrom is a water tank 21 having a transverse series of nipples 22

depending from the bottom of the tank and extending within suitable openings in the top 7 of the casing, by means of which communication is established between the water tank and the interior of the casing to permit the water to be fed upon the mop or scrubbing element 15. Journalized between the side walls of the tank 21 is a transverse shaft 23 having a plurality of crank portions 24 with which the valves 25 are associated, the cranks being normally so disposed that the valves extend within the nipples 22 thereby cutting off communication between the water tank and casing respectively. The shaft 23 projects a slight distance beyond one side of the water tank, and fixed upon the extremity of the shaft is a lever 26 for the purpose of operating the shaft to open and close the valves as the occasion may require. The tank is provided with an enlarged central filling opening which is normally closed by means of a cap 27. The tank is further provided at its opposite ends with handles 28 for the purpose of removing the tank 25 from the casing when desired.

The forward end of the casing is provided with a compartment 29 for the reception of a cleaning substance such as powder or the like, which is adapted to be distributed over the surface to be cleaned in advance of the scrubbing element 15. Mounted within the compartment 29 immediately adjacent the bottom thereof is a rotor 30, the shaft 31 of which projects beyond the side of the casing 30 and has fitted thereon a pulley 32 which is connected by means of the belt 33 with a pulley 34 fitted upon the foremost shaft 10, whereby the rotor 30 is operated simultaneously with the movement of the machine 40 over the surface to be cleaned. The rotor serves to discharge the cleaning substance through suitable openings 35 in the bottom of the compartment, the particular amount discharged being controlled by a slide plate 45 mounted beneath said bottom and provided with a plurality of openings 37 which are adapted to be brought into and out of registry with the openings 35. The plate 36 is provided with a handle 38 for the purpose 50 of adjusting the plate as described.

Arranged at a suitable point within the casing is a wringer consisting of a pair of superimposed rollers 39 normally held closely associated by means of the spring 55 40, and between which rollers the upper run

of the scrubbing element passes. These rollers serve to wring the dirty water from the mop or cleaning element 15, which dirty water is received within a suitable receptacle 41, positioned immediately beneath the said 60 rollers. Extending from the bottom of the receptacle 41 adjacent the opposite sides of the machine are pipes 42 which lead to a tank 43 at the rear of the machine, and through which pipes the dirty water from the receptacle 41 is directed to and deposited within the tank 43. The bottom of the tank 43 is provided with a drain opening 44 which is normally closed by means of a plug 45 mounted on the lower end of a rod 46, and by means of which the plug may be removed from the opening to permit of the discharge 65 of water from the tank when desired.

It will be manifest from the foregoing description that I have devised a machine of 75 the character described, which is not only very efficient for the purpose intended, but by means of which a floor or other surface may be expeditiously cleaned or scrubbed at ease. It is believed that from the foregoing the nature and advantages of the invention will be thoroughly understood without requiring a further explanation and therefore the same has been omitted.

What is claimed is:—

A floor scrubbing machine comprising a bottomless casing, a pair of transverse rollers journalized therein, an endless scrubbing member trained about said rollers, a transverse shaft extending between said rollers 90 and beyond the sides of the casing, a handle secured on the outer ends of said shaft, and means for resiliently urging the lower run of said scrubbing element into engagement with the floor, said means comprising a pair 95 of transverse rods disposed within aligned vertical slots in the sides of the casing, a plate bearing upon the upper side of the lower run of said scrubbing element and having its ends inclined upwardly 100 and coiled about said transverse rods, and an upwardly bowed spring member bearing against the lower side of said transverse shaft having its ends coiled about said rods.

In testimony whereof I affix my signature 105 in presence of two witnesses.

Mrs. HELEN M. DEAM.
